UNITED STATES PATENT OFFICE.

HARRY C. GAMMETER, OF CLEVELAND, OHIO, ASSIGNOR TO THE AMERICAN MULTIGRAPH COMPANY, OF CLEVELAND, OHIO, A CORPORATION OF OHIO.

PRINTING MECHANISM.

1,006,544.

Specification of Letters Patent. Patented Oct. 24, 1911.

Application filed October 22, 1906. Serial No. 339,909.

To all whom it may concern:

Be it known that I, HARRY C. GAMMETER, a citizen of the United States, residing at Cleveland, in the county of Cuyahoga and State of Ohio, have invented a certain new and useful Improvement in Printing Mechanism, of which the following is a full, clear, and exact description, reference being had to the accompanying drawings.

0 This invention relates to printing machines of the type commercially known as the multigraph, wherein there is a rotary printing drum adapted to carry individual type and a suitable platen coöperating therewith.

The features comprised in the present invention are the means for properly locating the type on the drum and holding them against endwise displacement; the mechanism for guiding the sheet as it passes between the drum and platen, and the mechanism for finally ejecting the paper so arranged that it and the means for holding the type are adjustable lengthwise of the drum, so as to allow the assemblage of matter of different widths and the ejection of paper corresponding thereto.

The object of the invention is to present these features in simple and efficient mechanism. Such mechanism is hereinafter more fully described in connection with the drawings.

Figure 1 is a front elevation of the printing portion of a multigraph embodying this invention; Fig. 2 is a vertical section through the same; Fig. 3 is an enlarged vertical section parallel with Fig. 2, showing the paper feeding mechanism; Fig. 4 is a vertical section of the parts shown in Fig. 3, looking from the other direction; Fig. 5 is a vertical cross section in a plane parallel with Fig. 4, showing the paper ejecting rolls; Fig. 6 is a rear elevation of the paper ejecting device; Fig. 7 is a plan taken just above the impression platen and showing the lower members of the paper feed and the paper ejection mechanism; Fig. 8 is a vertical section through the guide for the edge of the paper, being taken on the section line 8-8 of Fig. 7; Figs. 9 and 10 are sections showing the lock for the adjustable cam which controls the paper feed, these views being taken on the correspondingly numbered

lines of Fig. 1; Fig. 11 is a perspective view of the block forming a portion of such lock; 55 Fig. 12 is a detail showing a cross section of a portion of the drum together with the fastening devices of the type holding band; Fig. 13 is a perspective view of the type holding band, the same being broken out intermittently, and Fig. 14 is a perspective of the edge guide for the paper. 60

In the embodiment shown, in the drawings, there is a suitable base A from which rises a pair of vertical parallel standards or 65 end plates A' and A''. Journaled in these plates is a main driving shaft B on which is mounted the printing drum B'. The surface of this drum as shown in Fig. 12 is provided with undercut grooves b for the 70 reception of type C which have laterally extending feet, whereby they may slide lengthwise of the grooves but are held therein against lateral and outward movement.

Any suitable means is provided for allowing the type to be assembled on the drum. Fig. 1 shows at a' a suitably formed guiding channel across the frame member A' by which the type may be slid to and from the printing drum. Beneath the printing drum 80 is a rotary impression platen D connected with the drum by gears b' and d' on the drum and platen respectively. The drum has a considerable opening in its periphery, adjacent to which it carries a pair of spools 85 E. A suitable inking ribbon is adapted to be carried by these spools passing around the drum. A crank B² is shown as providing means for rotating the drum. When the drum, having type assembled on it and 90 a ribbon passed around the type, is rotated, paper may be drawn between the drum and platen and thereby be printed.

As the type are freely slidable along the drum, it is necessary to have some means 95 to prevent their displacement, and this means should be so devised that it may be adjustably positioned on the drum to allow matter of different widths to be assembled thereon. This type holding means must also 100 be of such character that it does not project farther than the type, so that it may pass between the drum and platen without impressing or marring the paper. I have found that the desired results may be very 105 efficiently accomplished by one or more steel

bands F each of which is provided at its end with hooks f. These bands are passed around the drum adjacent to the ends of the lines of type thereon and the hooks are hooked over the edge of the drum at the opening therein, as shown in Figs. 1 and 12. The hooks f may be very conveniently made of wire bent into a U shape intermediately and having the ends crossing each other and passing toward each other into a tubular eye f' formed by rolling over the end of the band.

To allow the band F to be properly positioned, I provide suitable marks b⁴ on the drum, these marks occurring at regular intervals, say at distances equal to five type. These marks are extended around the drum, preferably on the bases of the type grooves, as indicated by the dotted lines in Fig. 1. By means of the bands the matter on the drum may not only be very conveniently locked to the drum, but the bands being accurately positioned by the guiding marks, the proper and uniform margin is maintained for all the lines. Short lines, as at the ends of paragraphs, may be held at one end by suitable rubber plugs set into the grooves, as is well understood.

The mechanism which grips the paper and feeds it, including the feed rollers and stop fingers herein shown, is the subject of my Patent No. 846,992 granted March 12, 1907. The mechanism for controlling such feed rollers and timing thereof shown herein is covered in my divisional application No. 396,571, filed Oct. 9, 1907. For completeness, both mechanisms will be described herein.

As shown in Figs. 2, 3, 4, and 7, g represents a shaft on which are mounted sleeves G forming an interrupted roller projecting plate through openings in a horizontal frame plate A³ constituting a table. This roller has a gear g' meshing with an idler g² which meshes with the gear d' on the platen. Above the rollers G is a roller H mounted at its ends in pivoted arms, of which the right hand one is shown at H'. This arm H' is extended inwardly and carries a roller h which is adapted to be engaged and depressed by a cam K carried by the printing drum. Such depression maintains the roller H out of engagement with the rollers G, as shown in Fig. 3.

J represents fingers adapted to project through openings in the table A³, these fingers being rigidly mounted on a rock shaft j. A spring j' surrounding this rock shaft tends to keep the fingers with their upturned ends projecting above the plane of the table and into engagement with the roller H. On the forward end of the arm H' is an extension h' which has a downwardly extending lug adapted to bear on a rock arm j² on the shaft j. When the parts are

in the position shown in Fig. 3 (the cam engaging the roller h) the sheet of paper is shoved by hand across the front portion of the table A³ until its rear edge is stopped by fingers J.

When the cam clears the roller a spring h² swings the cam roller upward, bringing the forward end of the arm H' downward. This movement through the extension h' swings the rock shaft j and draws the fingers J downwardly out of the way of the paper. At the same time the roller H descending, comes on the paper and moves it between itself and the rollers G, these latter rollers being constantly revolving to feed the paper so that it passes between the drum and the impression platen. The forward end of the spring h² engages in a series of notches in a stationary bar h³, whereby the force of the spring may be adjusted. The paper feed mechanism is partly hidden from view by the shield and paper guide a² carried at the front of the machine.

When the sheet of paper is placed in position against the fingers J, one edge of the paper at least lies beneath the metal strip N. This strip extends from beneath the roller H rearwardly across the barrel d³ of the impression platen and adjacent to the soft surface d² thereof. Beneath the strip N is a strip N' the forward portion of which curves downwardly around the upper part of the platen barrel, the two strips extending rearwardly in parallelism from a point adjacent to the highest line 100 of the platen. The parallel portions of the two strips are brought together at their outer edges and are carried by a sheet metal bracket N² which is secured to the table plate A³. In the preferred form, the two strips N N' and the bracket are a single integral piece of sheet metal bent on itself as shown in Fig. 14. This guiding structure is supplied at each end of the raised surface to the impression platen. If the paper is 110 of a full width each edge is guided by these strips. If the paper is narrower than the full width, one edge is guided, which has been found sufficient.

It is desirable to maintain the feed rolls 115 out of coöperation during a considerable portion of the rotation of the drum so as to allow ample time for placing the sheet against the stop fingers; and it is also desirable to regulate the time of beginning 120 the paper feed to accommodate various sizes of letter heads. To accomplish this, I provide the cam mechanism which operates the lever H' in the form of two adjustable parallel rings K K', mounted on the drum. 125 These rings have corresponding cam surfaces. If the rings are positioned with their cam surfaces side by side, they act as a single cam, holding the rolls out of engagement for a portion of the rotation corre- 130

sponding to the length of the cam. The roll h , however, is broad enough to extend across both cams,—wherefore should one cam be shifted beyond the other, the effective length of the cam is increased up to a maximum of twice the length of either cam member. By this means the paper feed may be held out of action for as great or short a period as desired. One of the cams is stationary and is of a length corresponding to the minimum it is desired to have the rollers out of engagement. Something less than twice this minimum constitutes the maximum time desired non-engagement of the rollers, wherefore the two cam members, constituting in effect a "telescoping" cam, supply the desired results.

The mechanism for locking the cam members in desired position is shown in Figs. 1, 2, 9, 10 and 11. In the end member b^s of the drum, adjacent to the surface b^s on which the cams seat, is a recess adapted to be occupied by a block L . This block has a shoulder or rib l along its upper edge which is adapted to occupy a corresponding notch in the cam ring K' , thereby securely locking this ring to the drum. The block extends outwardly beneath the cam ring K . In the block is a threaded hole which is occupied by a cap screw l' . This screw passes through an L-shaped clip l^s , which bears on the outer side of the block and against the cam ring K and projects into the recess beneath the block, thereby holding the rib l in the notch in the cam ring K' . The cam rings are held by the gear b' and the body of the drum against movement longitudinally of the drum. The block holds the cam ring K' against rotative movement, and the cam ring K holds the block against displacement by reason of the shoulder l . When the cap screw l' is loosened, the cam ring K is thereby unlocked and may be shifted circumferentially to shorten or lengthen the effective cam, as desired. A recess k is made in the inner face of this cam to allow the insertion of a screw driver or other tool for conveniently shifting the cam.

By reason of the L-shaped clip l^s , the locking block L may be easily put in place. The height of the shoulder l is slightly less than the thickness of the piece l^s . Wherefore when this piece is removed, the block may be slid into the recess beneath the cam ring K , the block then being moved outward radially, the rib l passes into place behind the ring K . The piece l^s is then put into place as a filler to hold the block in this position.

When the movable cam K has been adjusted and locked to properly time the paper feed according to the letter head on the paper, a rotation of the drum causes the paper to be fed rearwardly between the drum and platen, one or both edges of the

paper passing between the strips of the edge guide or guides. In such operation, it sometimes happens that the friction of the sheet of paper develops sufficient frictional electricity to give it a tendency to cling to the printing drum, so that as the paper emerges from the guiding strips, it is carried around toward the front of the machine by the printing drum, and unless removed, will again pass through the printing mechanism. 75 This difficulty does not ordinarily occur, but in cold dry weather it sometimes happens, especially if the paper be light and flexible. To overcome the difficulty mentioned, I provide an ejecting mechanism adapted to receive the paper as it is emerging from the printing couple, and prevent its wrapping around the drum. This mechanism is shown in Figs. 2, 5, 6, and 7. Mounted on the end frame member A^s is a pinion p which carries a belt pulley. A belt p' connects this with a pulley p^s on the shaft p^s which is carried between the frame members, extending parallel with the platen, as shown in Fig. 6. This shaft is carried at one end by a removable stud p^t , extending into an opening in the shaft and at the other end by a screw p^s , which projects into an opening in that end of the shaft. This shaft p^s carries rollers P which project upwardly through openings in the table A^s . Extending horizontally across the machine near its rear edge is a rod Q on which are slidably mounted arms R in the form of cages which carry freely journaled rollers S adapted to bear upon the rollers P . The paper being fed rearwardly in a substantially horizontal plane along the top of the table, runs between the rollers S and P , which continue to guide it so that when the paper is freed 105 from the guiding strips, it is not able to come up onto the drum and cling thereto.

As heretofore stated, the bands F which I have provided allow matter of various size to be locked on the drum. For example, it 110 may be desired to print postal cards. In this case, one of the bands may be near the end of the drum and the other near the middle. Where the type page is of this short width, the paper is of correspondingly narrow width, and hence is guided by only one of the guiding clips at the ends of the platen. When the paper ejector is used, only one of the end rolls P would come into action with such narrow paper. I accordingly provide one or more intermediate rolls. In the embodiment shown, there is one intermediate roll P which is ordinarily sufficient, as it is seldom desirable to print on paper materially less than half the width of 125 the drum. But two rolls S need be provided, because their carrying members R are slidable upon the rod Q , so that the two rolls S may be made to coöperate with any two of the rolls P , according to the position 130

of the bands F on the printing drum. To furnish convenient means for shifting these rolls S, I form tails or extensions r on the members R by which they may be easily taken hold of by the fingers. Between the two ears of the cage, which surround the rod Q, I place a split sleeve r' which engages this rod with sufficient friction to prevent accidental displacement of the cage r, while 10 allowing it to be shifted when desired.

The parts constituting the paper ejector are made so that they may be conveniently removed when it is not desired to use them. When they are in place, it is simply necessary to position the cages or arms R with their rolls in accordance with the position of the bands F and the ejector is ready for use. 15

The ejecting mechanism *per se* is covered in my divisional application No. 459,348, filed Oct. 24, 1908; it is claimed herein only 20 in combination with the printing couple and the mutually adjustable marginal band.

I claim:

1. In a printing mechanism, the combination of a printing member, having longitudinal type holders, a band mounted on said member and adjustable to various lateral positions to lock the type against longitudinal displacement, paper feeding mechanism, and a paper ejecting mechanism adjustable for different widths of paper corresponding to the position of the type as held by said band. 25

2. In a printing mechanism, the combination of a rotary printing drum having longitudinal type holders, a peripheral band adjustably mounted on said drum to lock the type against longitudinal displacement, paper feeding mechanism, an adjustable cam 30 on the drum to control the paper feeding mechanism, and a paper ejecting mechanism adjustable for different widths of paper corresponding to the position of the type margin defined by said band.

3. In a printing mechanism, the combination of a rotary printing drum having longitudinal type holders, a pair of peripheral bands mounted on said drum to lock the type against longitudinal displacement, at 35 least one of said bands being laterally adjustable, and a paper ejecting mechanism adjustable for different widths of paper corresponding to the position of the type as held by said bands.

4. In a printing mechanism, the combination of a printing member having longitudinal type holding channels, type in said channels, a band mounted on said member and adjustable to various lateral positions to 40 engage the ends of successive type rows, paper feeding mechanism, and a paper ejecting mechanism adjustable for different widths of paper corresponding to the position of the type held by said band.

5. In a printing mechanism, the combina-

tion of a rotary printing drum having a recess and longitudinal type holders, a pair of peripheral bands having at their ends hooks engaging the drum adjacent to said recess, to lock the type against longitudinal displacement in either direction, paper feeding mechanism, an adjustable cam on the drum to control the paper feeding mechanism, and a paper ejecting mechanism adjustable for different widths of paper corresponding to the position of the type held by said bands. 70

6. In a printing mechanism, the combination of a printing member, having fixed holders for lines of individual type, and a marginal band adapted to be carried by said member and adjustable to various lateral positions, and extending across the face of the member and abutting the ends of various type lines and projecting less distance 75 than the type thereon.

7. In a printing mechanism, the combination of a channeled printing member adapted to carry rows of individual type and a flat metallic band adapted to extend across the face of such member adjacent to the type to hold the same against longitudinal shifting, and hooks on the ends of said band for securing said band to said member. 90

8. In a printing mechanism, the combination of a rotary drum having longitudinal type holders and a flat band removably carried by the drum and adapted to be held around the same peripherally adjacent to the ends of the lines of type in varying position according to the length of those lines. 95

9. In a printing mechanism, the combination of a printing member having a series of parallel rails adapted to carry rows of type, an impression platen adapted to co-operate therewith, there being marks on the member between the rails crosswise of the rows, and a metallic band adapted to be adjustably positioned on said member according to said marks. 105

10. In a printing mechanism, the combination of a printing drum having longitudinal channels adapted to carry type, an impression platen adapted to co-operate therewith, there being peripheral marks on the drum at the base of said channels, and a metallic band adapted to be adjustably positioned on said drum according to said marks. 115

11. In a printing mechanism, the combination of a printing member adapted to carry rows of type, there being marks on the member crosswise of the rows, a metallic band adapted to be adjustably positioned on said member according to said marks, and a paper ejecting mechanism adapted to be positioned in correspondence with the position of the metallic band. 125

12. In a printing machine, the combina-

tion of rotary mechanism formed to carry parallel rows of individual type and a marginal band adapted to be mounted thereon and abutting the ends of the rows and adjustable to various lateral positions across the face of said mechanism and projecting less distance than the type thereon.

13. In a printing mechanism, in combination, a rotary drum, a series of longitudinal type holding rails thereon, and a series of 10 peripheral marks between the rails occurring at regular intervals about the periphery of the drum, and a flat band adapted to be held on said drum adjacent to said 15 marks.

14. A rotary printing drum formed to carry individual type on its surface, a flat band adapted to extend peripherally about the drum adjacent to the type and project 20 less distance than the height of the type, and hooks for locking the ends of said band to the drum.

15. A rotary printing drum having a recess and formed to carry type on its surface, a band adapted to extend around the periphery of the drum adjacent to the type and project less distance than the height of the type, and hooks on the ends of said band adapted to hook onto the edge of the drum 30 at such recess.

16. In a printing mechanism, the combination of a rotary channeled drum, type adapted to be carried thereby, said type and channels being formed to retain the type 35 against radial and lateral movement while allowing longitudinal movement, a platen coöperating with the drum, and a flat metallic band adapted to lie about the periphery of the drum adjacent to the ends of the 40 lines of type in the channels, and pass with the type across the platen but out of engagement therewith, and means for holding said band to said drum.

17. A printing member, adapted to carry 45 individual type in parallel rows, a flat band adapted to extend transversely of said rows at their ends and abut them and project a less distance than the type, and hooks car-

ried by said band for locking the ends of said band.

18. The combination with a rotary printing couple, of a paper feeding mechanism on one side of the couple, a paper ejecting mechanism on the other side, and an edge guide for the sheet adapted to receive the 55 sheet from the feeding mechanism and deliver it to the ejecting mechanism said edge guide consisting of two strips adapted to lie above and below the paper and extend continuously through the couple.

19. The combination of a rotary printing couple, paper feeding mechanism on the front side thereof, paper ejecting mechanism on the rear side thereof, and paper stripping mechanism located substantially 65 at the line of contact of the printing couple engaging both the upper and under sides of the paper and extending continuously from one side of the couple to the other.

20. The combination, with a printing 70 member, of a flat marginal band adapted to be carried thereby intermediate of the edges of the member, for defining the ends of the type lines, and means on the printing member for carrying rows of individual type at 75 right angles to the band.

21. The combination with a printing member arranged to carry rows of individual type, of a flat metallic band mounted on the member and arranged to have its edge 80 abut and define the ends of such lines, the band projecting less height than the type, and a hook provided on the end of the band to lock it to the printing member.

22. The combination with a member 85 adapted to carry lines of type, a flat band adapted to engage the ends of such lines, a hook on the end of such band adapted to swing over and engage the edge of the type holding member.

In testimony whereof, I hereunto affix my signature in the presence of two witnesses.
